UNITED STATES PATENT OFFICE.

GEORGE W. FISHER, OF FREELAND, MARYLAND, ASSIGNOR OF ONE-THIRD TO CHARLES W. MONTGOMERY, OF WASHINGTON, DISTRICT OF COLUMBIA.

WINDOW-SCREEN.

1,243,928.

Specification of Letters Patent. Patented Oct. 23, 1917.

Application filed March 12, 1917. Serial No. 154,311.

To all whom it may concern:

Be it known that I, GEORGE W. FISHER, a citizen of the United States, residing at Freeland, in the county of Baltimore and 5 State of Maryland, have invented certain new and useful Improvements in Window-Screens; and I do declare the following to be a full, clear, and exact description of the invention, such as will enable others skilled 10 in the art to which it appertains to make and use the same.

My invention relates to improvements in window-screens of the type which are automatically stretched for use when the window 15 sash is raised, and the principal object is to provide a novel arrangement of parts whereby the screen extending means may be thrown out of action at will to permit raising of the sash without stretching the screen 20 over the opening thus formed.

With the foregoing general object in view, the invention resides in certain novel features of construction and unique combinations of parts to be hereinafter fully 25 described and claimed, the descriptive matter being supplemented by the accompanying drawings which constitute a part of this application and in which:

Figure 1 is an inner side elevation of a 30 window and the improved screen applied thereto;

Fig. 2 is a fragmentary elevation similar to Fig. 1 with one of the ordinary sash guiding beads broken away to more clearly illustrate the driving pinion for the roller upon which the screen is wound;

Fig. 3 is an enlarged elevation of one 40 lower corner of the window with parts broken away and in section;

Fig. 4 is an enlarged vertical transverse section on the plane of the line 4—4 of Fig. 3;

Fig. 5 is a horizontal section substantially 45 on the plane indicated by the line 5—5 of Fig. 3, showing the driving pinion in mesh with its rack bar;

Fig. 6 is a similar view showing the pinion shifted out of mesh with said bar;

Fig. 7 is an enlarged vertical section on 50 the plane of the line 7—7 of Fig. 1;

Fig. 8 is an inner side elevation of the lower end of the lower sash;

Fig. 9 is a perspective view of the pinion shifting means and the guide thereof;

55 Fig. 10 is a perspective showing the lower

end of the specially constructed guide strip which carries the rack bar for operating the roller driving pinion.

In the drawings above briefly described, the numeral 1 has reference to an ordinary 60 window-frame while 2 and 3 designate respectively the upper and lower sashes thereof which are mounted slidably in the usual manner and guided by suitable strips or beads. One of these beads is identified in 65 the drawing by the numeral 4 and is of greater size than those usually employed and of special construction to be described.

The lower end of the lower sash 3 carries a metal casing 5 extending throughout the 70 width of the sash and open at its inner side as illustrated most clearly in Figs. 5 and 7, said casing receiving therein a roller 6 to which the upper end of an appropriate screen 7 is secured, the other end of said screen having 75 a reinforcing strip 8 coacting with a pair of pivoted latches 9 located adjacent the sides of the frame. The function of the latches 9 is to hold the strip 8 in engagement with the sill 10 of the frame 1 in order that raising of the sash 3 may project the screen 7, said screen being totally wound on the roller 6 when said sash is lowered.

For rotating the roller 6 to rewind the screen 7 thereon when the sash 3 is lowered, 85 a pinion 11 and a vertical rack bar 12 are provided, said pinion being carried on one end of said roller whereas the bar 12 is inset in the inner side of the bead 4 as illustrated most clearly in Figs. 4, 5 and 10. 90 These parts also mechanically rotate the roller 6 to unwind the screen when the sash is raised, the proportion of parts being such that when said sash is elevated to the maximum, the screen will be stretched taut over 95 the open space below said sash.

It is often desirable to raise the sash 3 without moving the screen to operative position and novel provision is made for permitting such operation. The pinion 11 is 100 slidably mounted on one end of the roller 6, which end is preferably squared as shown at 13, a suitable means being provided for shifting said pinion into and out of mesh with the rack 12 at will, in order that it 105 may be rotated or may remain idle as occasion may demand. When the pinion is shifted out of engagement with the rack, it travels in a vertical groove 14 in the inner side of the bead 4 whenever the sash 3 is 110

raised or lowered. When the pinion is moved to this position, the latches 9 are released to permit the entire screen to move bodily with the sash.

5 Since it is undesirable to have the pinion 11 shifted either into or out of mesh with the rack 12 when the sash is raised, the shifting means for said pinion is carried by the sill 10 and is operable only when said sash 10 is lowered, said means being shown in the form of a slide 15 having a fork 16 received in a groove 17 on the hub of the pinion 11, one end of said slide having an upstanding operating handle 18 which rises through a 15 slot 19 in the usual finishing strip 20 secured to the upper surface of the sill 10 (see more particularly Fig. 5). The slide 15 is mounted on parallel tracks 21 inset in a shallow channel 22 formed in the upper side of the 20 window sill and said tracks are preferably formed integrally at one end with an attaching plate 23. By the arrangement of parts described, the hub of the pinion 11 will move from the fork 16 when the sash is raised and thus said pinion cannot be shifted until the 25 sash is again lowered. When lowered, however, shifting of the handle 18 will move pinion 11 into or out of mesh with its rack bar 12 as occasion may demand.

30 From the foregoing, taken in connection with the accompanying drawings, it will be observed that although the invention is of comparatively simple and inexpensive nature, it will be efficient and convenient.

35 Since these advantages are best derived from the construction shown and described, this arrangement constitutes the preferred form of the device. It is to be understood, however, that within the scope of the invention 40 as claimed, numerous changes may be made without sacrificing the principal advantages.

I claim:

1. In combination, a window-frame, a sash 45 slideable vertically therein, a roller mounted on said sash, a screen wound on said roller, means for detachably securing the free end of said screen to one end of the frame, means for rotating said roller when the sash is opened or closed, including a fixed unit carried by the frame, a shiftable unit movable

with the sash, and means at one end of the frame for shifting said movable unit into and out of operative relation with said fixed unit when the sash is closed.

2. In combination, a window-frame, a sash 55 slideable vertically therein, a roller mounted on said sash, a screen wound on said roller, means for detachably securing the free end of said screen to one end of the frame, means for rotating said roller when the sash is 60 opened or closed, including a rack bar carried by the frame and a shiftable pinion movable with the sash, and means at one end of said frame for shifting said pinion into and out of mesh with said rack bar when 65 said sash is closed.

3. In combination, a window-frame, a sash 70 slideable vertically therein, a roller mounted on said sash, a screen wound on said roller, means for detachably securing the free end 75 of said screen to one end of the frame, means for rotating said roller when the sash is opened or closed, including a rack bar carried by the frame and a pinion mounted slidably on one end of said roller, the hub 80 of said pinion having a peripheral groove, and a shiftable fork mounted at one end of the frame for reception in said groove when the sash is closed to permit shifting of said fork to correspondingly shift the pinion into 85 or out of mesh with said rack bar.

4. In combination, a window-frame, a sliding sash therein, a roller mounted on said sash, a screen wound on said roller, means for detachably securing the free end of said 85 screen to one end of said frame, a pinion rotatable bodily with and slideable longitudinally of said roller, a rack bar carried by the frame for co-action with said pinion to rotate said roller, and means for sliding said 90 pinion into or out of mesh with said rack bar.

In testimony whereof I have hereunto set my hand in the presence of two subscribing witnesses.

GEORGE W. FISHER.
